UNITED STATES PATENT OFFICE.

HENRY MOECKER, JR., OF HOMEWOOD, AND JOHN VAN ES, OF HARVEY, ILLINOIS, AS
SIGNORS TO AMERICAN STOVE COMPANY, OF ST. LOUIS, MISSOURI, A CORPORATION
OF NEW JERSEY.

HYDROCARBON BURNER.

Application filed December 21, 1926. Serial No. 156,198.

This invention relates to improvements in hydrocarbon burners and pertains to a construction that is especially adapted to use gasoline, but in which it is possible that heavier oils might be used.

One feature of the present invention is extending an oil retort tube entirely across the top of the burner through which the oil passes, a mixing chamber below the said tube and parallel with it, the mixing tube having its rear end communicating with the rear end of the burner, and a valved passageway having communication with the forward end of the oil retort tube and with the front end of the mixing chamber, whereby the vapor is mixed with air in the mixing chamber and fed to the burner, the burner heating the tube thereabove.

Another feature of the invention is locating a retort tube above and adjacent a burner, a mixing chamber below the burner and extending parallel with said retort, a valved passageway located at the front of the burner and having communication with the front end of the retort and with the said mixing chamber, the opposite end of the mixing chamber communicating directly with the burner and also with a passageway adapted to feed an auxiliary burner or burners.

Another feature of the present invention is to connect to the front end of the retort tube a vertical coil which has its upper end communicating with the front end of the retort tube and its lower end communicating with the valved passageway which in turn is in communication with a mixing chamber located under the burner and having communication with the said burner, and means located below the said coil and valved passageway for initially starting the operation of the valved passageway and burner.

A further object of the invention is to provide a hood that surrounds the vertically connected horizontal retort tube and the valved passageway, and means located below the said coil for heating it, whereby the hood conserves the heat around the said coil for initially starting the burner.

Further improved features will be pointed out in the following description.

In the accompanying drawings:

Figure 1 is a sectional elevation substantially full-size of our improved burner and its operating parts. 55

Figure 2 is a top plan view of the said burner showing auxiliary burners connected therewith.

Figure 3 is a central sectional view on the line 3—3 of Figure 1. 60

Figure 4 is a horizontal sectional view on line 4—4 of Figure 1.

In carrying out the present improvement we provide a burner 1 and a retort tube 2 that extends across the burner from its rear 65

to its front end. The rear end 3 of the retort tube 2 is in communication with a suitable pressure reservoir (not shown) containing the oil that flows from the said reservoir into the retort. Located below the burner 70

1 is a mixing tube 4 that has its rear end provided with a chamber 5 which is an enlargement of the said tube. From the plan view in Figure 2 it will be observed that the burner has a rearwardly extending projection 6 which is hollow as shown in Figure 1, the said portion 6 communicating with an opening 7 formed in the top of the chamber 5. This chamber 5 also has an opening 8 that extends transversely of the mixing tube 80

4 and communicates respectively with two tubes 9 and 10, that have their rear ends 11

and 12 communicating with the rear ends 13

and 14 of auxiliary burners 15 and 16. 75

Referring now to Figure 1, the burner 85

1 is made hollow and preferably has a central vertical opening 17 extending there-

through, the body portion of the burner is provided with a plurality of vertical

burner slits 18. 80

The rear end of the retort tube 2 is preferably reduced by a suitable member 19 as shown in Figure 3. Oil passing through this reduced portion flows into the tube 2 where it is immediately vaporized, as will be 95

more fully referred to hereinafter.

A suitable coil 20 has its lower end communicating with a valved passageway 21 and its upper end communicating with the upper end of the retort tube 2. Located in this valved passageway 21 is a screw threaded 100

rod or member 22 that carries at its forward

end a suitable valve 23 by means of which the opening 24 is controlled. It will be observed that the coil 20 communicates with the passageway at a point intermediate the 5 said passageway whereby the valve 23 serves to close off the flow of vapor and oil through the opening 24. In this connection I utilize a nipple 25 that extends into the mixing tube 4, that has a small opening 26 that a pin 27 10 passes through when the valve is closed. Those skilled in this art understand the function of the pin is to keep clean the opening 26 when the valve is closed so that when it is opened the opening will be free for the 15 passage of vapor through it.

A suitable receptacle 28 is sustained below the coil 20 and the receptacle contains a suitable amount of mineral wool 29 for the purpose of being saturated and lighted. 20 In operation the valve 23 is closed and the mineral wool 29 saturated with alcohol, gasoline or the like, and then lighted by a match. The flame flowing upward from this mineral wool, strikes the coil 20 and incidentally warms it and the outlet end of the valved passageway. This coil being heated by the flame from the mineral wool, the oil therein is converted into a vapor. Then by 25 opening the valve 23 the vapor from the coil flows into the heated end of the valved passageway and through the nipple 25 into the mixing chamber 4. From this mixing chamber the mixed vapor and air flow through the opening 7 and strikes against the 30 perforate part 6, and then flows into the burner. The burner then being lighted, the retort tube 2 becomes heated and vapor is generated in the tube and flows into the coil and through the valved passageway to the 35 mixing chamber in the manner just explained. In initially starting the burner the valve 23 is closed and the mineral wool 29 is saturated with a volatile liquid and lighted. The flame and heat from the wool 40 heats the outlet end of the passageway 21 and heats the coil 20. Attention is called to the fact that this coil 20 is much smaller than the tube 2 and is made of such material that the coil becomes quickly heated. Said 45 heat and flame are concentrated around the coil by means of an upwardly inclined hood 30, the said hood beginning substantially at the passageway 21 and extends upward, its upper end 31 resting on the front end of the retort tube 2. The hood vertically surrounds said coil and has its inner end 32 50 clamped to a bracket 33 that extends downward from the underside of the burner 6. The upper end 34 of this bracket turns inward and is attached to the underside of the burner by means of a suitable screw or bolt 35. The inner end of the passageway 21 is provided with a rearward extending portion 36, which is clamped to the bracket 33 by 55 means of suitable screws 37.

The rear and inlet end of the retort tube 2 is supported upon a suitable bracket 38, the lower end of the bracket turned laterally and fastened by a suitable bolt or screw 39 to the rear end of the chamber 5.

We find that the coil is very efficient for initially starting the burner. It heats quickly from the flame produced by the fluid in the mineral wool 29 so that when the valve is opened any hydrocarbon contained in the coil is vaporized so that when the valve 23 is opened, vapor at once flows into the mixing tube 4, thence to the chamber 5 at its rear end and through the opening 7 into the burner 6. The flame from the burner 80 at once heats the retort tube so that the fluid in the retort is vaporized, which causes at once ample vapor for the operation of the burner and ample for the auxiliary burners.

The six pointed star shaped burners we 85 find to be exceedingly efficient, and gives a better result than the ordinary substantially round-shaped burners.

We call attention also to the shape of the chamber 5 at the rear end of the mixing tube. 90 This chamber forms in effect a pocket to receive any condensation of the vapor in the starting of the burner. When the burner is started, the mixing tube and passageway and the tubes 9 and 10 that connect with the auxiliary burners 16, are relatively cold, so that a very small portion of the vapor entering these parts will be in the first instance condensed, and by means of shaping the chamber 5 to form a pocket, this condensed hydrocarbon will be contained in the chamber 5 which prevents it from reaching the burners. When the burner becomes heated, then this condensed hydrocarbon becomes heated and is vaporized so that it 95 will not continue to accumulate in the said chamber.

By reference to Figure 2 it will be seen that the auxiliary burners 15 and 16 have the same shape as the burner 1 so that they 100 operate exactly as the burner 1 operates.

It is found in operation that the burner herein disclosed is very quickly started and when in operation provides ample vapor for the main burner and for the auxiliary burners. Located between the main burner and the auxiliary burners in any desired position are handles 40. These handles are for operating valves (not shown) that control the flow of vapor to the respective auxiliary burners. By means of these handles one or both of the auxiliary burners may be cut off, or supplied with vapor.

We have explained in considerable detail the preferred construction used in carrying out our improvement, but we desire it understood that variations may be made so long as those variations will come within a fair interpretation of the appended claims.

Having thus described our invention,

what we desire to claim and secure by Letters Patent is:

1. A hydrocarbon burner comprising a burner housing, a mixing chamber located below the housing and extending throughout its length, its rear end in communication with the burner housing, a retort tube extending over the said burner from its rear to its front end, a valve controlled passageway communicating with the front end of the mixing chamber, the passageway located vertically below the retort, a vertical coil having its ends connected respectively with the passageway and with the front end of the retort tube, the rear end of the mixing chamber being enlarged to form a depending pocket for the condensed vapor substantially as described.
2. A hydrocarbon burner comprising a burner housing, a mixing tube located below the housing and extending throughout its width, a retort extending across the top of the burner, a valved passageway communicating with the front end of the mixing chamber, the retort and passageway being in a vertical line above each other, a vertical coil having its ends connected respectively with the passageway and with the front end of the retort tube, the burner housing having at its rear end a rearwardly projecting imperforate portion and the mixing chamber having communication with the housing immediately below the imperforate portion whereby the vapor is distributed within the burner and a lighter located vertically below the valved passageway and the said coil, the parts operating for the purpose specified.
3. A hydrocarbon burner comprising a burner housing, a mixing chamber below the burner housing, a retort tube extending

across the top of said burner, a vapor passageway connecting with the said mixing chamber and located vertically below the adjacent end of the retort, a vertically arranged coil comprising a horizontal spiral located immediately between the said passageway and the said retort and forming communication between said retort and said passageway, a valve controlling the passage of vapor from said passageway, an initial lighter located below and in a line with said passageway, and the said coil, said horizontal spiral being wider than the said vapor passageway whereby the said initial lighter quickly heats the passageway and the exposed portion of the coil and quickly supplies vapor to be fed to the mixing chambers and thence to said burner.

4. A hydrocarbon burner comprising a burner housing, a mixing chamber below the burner housing, a retort tube extending across the top of said burner, a vapor passageway connecting with the said mixing chamber and located vertically below the adjacent end of the retort, a vertically arranged coil comprising a horizontal spiral located immediately between the said passageway and the said retort and forming communication between said retort and said passageway, a valve controlling the passage of vapor from said passageway, an initial lighter located below and in a line with said passageway and the said coil, said horizontal spiral being wider than the said vapor passageway, said coil made of a pipe smaller in diameter than the retort tube and the vapor passageway.

In testimony whereof we hereunto affix our signatures.
